UMBRELLA RUNNER AND TIP CUP

Filed Jan. 31. 1923

John Rose, Inventor
By Samuel M. Smith

Attorney

Patented Oct. 7, 1924.

UNITED STATES PATENT OFFICE.

JOHN ROSE, OF ATLANTIC CITY, NEW JERSEY.

UMBRELLA RUNNER AND TIP CUP.

Application filed January 31, 1923. Serial No. 616,083.

To all whom it may concern:

Be it known that I, JOHN ROSE, a citizen of the United States, residing at Atlantic City, in the county of Atlantic and State of New Jersey, have invented certain new and useful Improvements in Umbrella Runners and Tip Cups, of which the following is a specification.

This invention relates generally to umbrellas, and it relates particularly to combined runners and tip cups for umbrellas.

The object in view is to provide a combined runner and tip cup so constructed and having the parts thereof so arranged that the movement of the runner, in addition to performing its usual functions, shall be capable in its sliding movements on the rod of the umbrella of releasing the runner from retention by the upper and lower catches by which the umbrella is held in an open or a closed position. A further object is to provide, in combination with the runner, a tip cup by which the tips of the ribs may be held closely to the rod when the umbrella is closed, such cup to be capable of movement independently of the runner in order to retain or release the rib tips without movement of the runner, and without operating the catch-releasing means.

The invention consists in a combined runner and tip cup having the novel features of construction and arrangement of parts substantially as hereinafter described and claimed, whereby the above specified objects are attained.

The preferred form of embodiment of the invention is illustrated in the accompanying drawing, though I do not limit myself to the specific details shown and herein described, as it will appear from an understanding of the construction involved that various modifications in the form and arrangement of the parts may be made without departing from the scope of the invention involved.

In the drawing:

Figure 1 is a view showing portions of a handle, ribs and stretchers of an umbrella, the combined runner and tip cup being shown, in section, in position on the rod to secure the rib tips;

Figure 2 is a sectional view, showing the tip cup moved toward the handle of the umbrella independently of the runner to release the rib tips, the rib tips being shown in dotted lines in a released position.

Figure 3 is a detail sectional view, showing the positions of the runner and lower catch when the runner and parts connected therewith are moved on the rod, away from the handle, to depress the catch, rendering the runner free to be moved on the rod to spread the umbrella; and

Figure 4 is a sectional view of a modified form of catch-releasing means.

In this drawing 1 represents the rod of an umbrella which is shown of a tubular form, and 2 represents the handle. Located toward the tip end of the rod is a catch 3 by means of which the runner is retained when the umbrella is raised, and adjacent to the handle is a catch 4 by which the runner is retained when the umbrella is closed.

The runner is made up of the crown portion 5, which may be of the usual form, and the sleeve portion 6 receiving and sliding on the rod, which has in its wall a slot 7 into which projects one or the other of the retaining catches 3 or 4, according to the position of the runner.

In the embodiment of my invention herein shown, the end of the sleeve extending toward the handle is provided with an abutment against which one end of a spring for operating a tip cup, as hereinafter described, bears. As herein shown, the abutment is in the form of a disk 8 having a central opening receiving the rod, which disk may be formed integrally with the sleeve. Surrounding the sleeve is a tip cup formed by the disk 10, which constitutes the bottom of the cup, and the flange 13, which forms the sides of the cup. The cup has extending from it a tubular portion 9 of a length to receive and enclose means for operating the retaining springs carried by the rod, a spring for maintaining the tip cup in its normal position, and the disk 8 on the runner. The disk 8 is retained in the cylindrical extension from the tip cup as by bending the end of the extension inward, forming a lip 11 against which the disk abuts.

The bottom 10 is disk-shaped and has a central projecting tubular extension 12 having an interior opening of a size to fit closely to the rod which extends through it. The cup is slidable on the sleeve 6 and, therefore, when the umbrella is closed the tip ends 19 of the ribs 18 may be brought toward the rod and be received and retained by the inclosing ring formed by the flange 13 of the cup by the movement of the cup first toward

the handle, allowing the positioning of the ribs, and then away from the handle to inclose the tips of the ribs. Interposed between the disk 8 and the bottom 10 is a spring 14 by which the parts are normally held in the positions shown by full lines in Figure 1 of the drawing, to retain the rib tips. The spring is compressed when the cup is moved to allow the rib tips to be brought close to the rod in a position to be inclosed by the flange 13, or to release the tips after engagement, and acts to return the parts to their normal relative positions after such movement.

15 In order that the depression of the spring catches 3 and 4 may be effected to free the runner to permit moving the parts of an umbrella from an open to a closed position, or vice versa, by sliding the runner and the described attached parts on the rod, means located within the extension from the cup are provided for this purpose. One form of the catch-depressing member is shown in Figures 1, 2 and 3 of the drawing, and one of a number of modified forms which may be employed is shown in Figure 4. The first consists of a cylinder 15, having abruptly tapered ends 16, arranged within the extension from the cup in such position that a sliding movement of the cup toward the handle, when the umbrella is raised, brings the inner face of the upper tapered end of the cylinder into contact with the catch 3, depressing it to free it from engagement with the runner. This movement of the releasing means allows the sliding of the runner on the rod toward the handle to close the umbrella. When the umbrella is secured in a closed position by engagement 40 of the catch 4 with the runner and the rib tips are retained by the flange 13, a movement first of the tip cup toward the handle will release the ribs, and then of the runner toward the tip end of the rod, releases the runner from the catch and then results in opening the umbrella, it being retained in the usual way in an open position when the runner is brought to a position to be engaged by the catch 3. The operative parts 45 of the catch-operating means are, as shown, spaced apart a sufficient distance to permit movement of the tip cup to release the rib tips without bringing those parts into contact with a catch extending through the runner sleeve. Therefore, the tip cup may be moved to secure or release rib tips when the ribs are in a closed position without detaching the catch by which the runner is then held.

50 In the modified form of the catch-operating means shown in Figure 4 of the drawing oppositely arranged hollow conical projections 17 extend from opposite ends of the extension 9 of the tip cup into the interior

thereof. The projections extend from the disk 8 and the bottom 10 respectively, and are so located that their inner faces are brought into contact with the catches 3 and 4 to depress them according to the position of the parts and to the direction of the sliding movement of the runner and tip cup.

I claim:

1. An umbrella runner having an abutment, a tip cup enclosing and slidable on the runner, and a spring interposed between the abutment of the runner and the bottom of the tip cup.

2. An umbrella runner having a sleeve portion provided with a disk, a tip cup provided with a tubular extension and slidable on the runner, the tubular extension enclosing the disk and being provided with means for retaining the disk therein, and a spring interposed between the tip cup and the disk.

3. An umbrella runner having a sleeve portion provided with a disk, a tip cup slidable on the sleeve and provided with a tubular extension receiving the disk, means for retaining the disk in the extension, and catch-operating means consisting of a cylinder having contracted ends enclosed by and retained in the extension.

4. An umbrella runner, a tip cup slidable on the runner and provided with a tubular extension, catch-operating means comprising oppositely disposed inclined contact portions located in the extension, and a spring by which the catch-operating means is normally held in inoperative position.

5. An umbrella runner, a tip cup slidable thereon and having a tubular extension, and catch-operating means comprising inclined contacting portions enclosed by the extension, the inclined catch-operating means being spaced apart, permitting sliding of the tip cup on the runner without bringing them into use, and a spring arranged to maintain the catch-operating means normally in inoperative position.

6. An umbrella runner, a tip cup having a tubular extension, arranged on the runner and movable therewith, and catch-operating means consisting of a cylinder having contracted ends located in the extension, enclosing the runner, and connected to the tip cup.

7. An umbrella runner having a sleeve portion provided with a disk, a tip cup provided with a tubular extension receiving the disk, means for retaining the disk in the extension, catch-operating means consisting of a cylinder having contracted ends surrounding the runner and connected to the tip cup, and a spring interposed between the disk and the tip cup.

In testimony whereof I affix my signature.

JOHN ROSE.
